AIR CUSHION VEHICLE

Melville W. Beardsley, Severna Park, Philip W. Jackson, Jr., Silver Spring, Alfred G. Anderson, Bethesda, and George W. Gilbert, Kensington, Md., assignors, by mesne assignments, to National Research Associates, Inc., Laurel, Md., a corporation of Maryland

Filed Nov. 9, 1961, Ser. No. 67,440

Term of patent 14 years

(Cl. D71—1)

FIG. 1.

FIG. 2.

FIG. 3.

FIG. 4.

FIG. 5.

FIG. 1 is a perspective view of an air cushion vehicle showing our new design;

FIG. 2 is a front elevational view thereof;

FIG. 3 is a rear elevational view thereof;

FIG. 4 is a top plan view of an air cushion vehicle; and FIG. 5 is a side elevational view thereof.

The grid pattern fragmentarily shown in FIGS. 1 and 2 covers the entire areas designated.

What is claimed is:

The ornamental design for an air cushion vehicle, as shown and described.
